DESIGN FOR A DIVIDED BAR CLOTHES HANGER

Gordon E. Hill, Sumner, Wash.

Application July 31, 1944, Serial No. 114,650

Term of patent 3½ years

(Cl. D80—8)

To all whom it may concern:

Be it known that I, Gordon E. Hill, a citizen of the United States of America, residing at Sumner, in the county of Pierce and State of Washington, have invented a new, original, and ornamental Design for Divided Bar Clothes Hangers, of which the following is a specification, reference being had to the accompanying drawing, forming part thereof.

I claim:

The ornamental design for a divided bar clothes hanger, substantially as shown.

GORDON E. HILL.
